UNITED STATES PATENT OFFICE.

HERBERT A. THORNDIKE, OF WASHINGTON, DISTRICT OF COLUMBIA.

JACK.

1,393,851.

Specification of Letters Patent. Patented Oct. 18, 1921.

Application filed November 3, 1919, Serial No. 836,673. Renewed February 23, 1921. Serial No. 447,226.

To all whom it may concern:

Be it known that I, HERBERT A. THORNDIKE, a citizen of the United States, and a resident of Washington, in the District of Columbia, have invented certain new and useful Improvements in Jacks, of which the following is a specification.

My invention is an improvement in jacks, and has for its object to provide a device of 10 the character specified, especially adapted for use with motor vehicles, and to be attached permanently in place on the axles, and to be normally out of operative position, but capable of being brought into operation 15 when desired, merely by the movement of the jack in its normal operation.

In the drawings:

Figure 1 is a side view of a portion of a motor vehicle provided with the improved 20 jack, the jack being shown in operative position,

Fig. 2 is a vertical section in a plane parallel with the axle,

Fig. 3 is a side view of the jack in inoperative position,

Figs. 4 and 5 are sections on the lines 4—4, and 5—5 respectively, of Fig. 2.

In the embodiment of the invention shown, a suitable casing is provided, the said 30 casing comprising a body 1, which is substantially rectangular in cross section, the top being closed by a plate 2, while the bottom is adapted to be closed by the foot 3 of the jack.

It will be noticed that the casing 1 is of 35 relatively great length, and relatively narrow width, and a screw 4 is journaled longitudinally of the casing at the top. This screw has intermediate its ends an annular 40 groove 5, and a cross pin 6 held in the casing, engages the groove, to prevent longitudinal movement of the screw.

The ends of the screw are oppositely threaded, as clearly shown in Fig. 2, and 45 upon each of the said ends there is mounted a nut 7. Each of these nuts has on its upper side an undercut rib 8, and these ribs engage within a similarly shaped groove 9 in the top of the casing, to guide the nuts and to 50 prevent downward movement thereof with respect to the casing, when the screw is turned. It will be obvious that when the screw is turned the nuts will be moved toward or from each other, in a direction depending upon the direction of motion of the 55 screw.

Each nut 7 has a pair of depending lugs 10 at its outer end, the said lugs being spaced apart from each other, and a system of lazy tongs 11 is pivoted to the lugs. The 60 system of lazy tongs is pivoted at its lower end to the foot 3 before mentioned, and at the center of the said foot, and the lazy tongs is composed of levers pivotally connected to each other the nuts and the foot, 65 in such manner that when the nuts are moved together the system as a whole is elongated, while when the nuts are moved apart the system is shortened. Thus when the nuts are moved together, the foot will 70 be moved away from the screw, while when the nuts are moved apart, the foot will be moved toward the screw, and when the system is fully contracted, the foot abuts against the lower edge of the casing and 75 closes the same.

In order to turn the screw to operate the lazy tongs a worm wheel 12 is secured to the extended end of the screw, and this worm wheel meshes with a worm 13 on a driving 80 shaft 14 to which the worm is keyed. This driving shaft 14 has one end polygonal as shown at 15, for engagement by a wrench or the like to turn the shaft. The driving mechanism for the screw namely the worm 85 wheel, worm and shaft 14 are arranged in an auxiliary housing 16, which is detachably connected to the casing 1, to permit its removal to inspect the worm gearing.

While it is obvious that the improved jack 90 may be used, and is suitable for use, in any connection where a jack is desired, it is especially adapted for use with motor vehicles, to form a permanent attachment in connection with the vehicle. With this object in 95 view I arrange a jack at each corner of the vehicle, that is near each end of each axle. In order to connect the jack to the axle, I provide in connection with each casing a sectional bearing, consisting of a section 16 100 rigid with the casing, and a section 17 detachably connected with the section 16, as indicated at 18. The sections 16 and 17 are adapted to embrace the rear axle housing and the front axle, and the bearings are 105 shaped to fit housing or axle as the case may be. In the present instance the bearings are shaped to fit the housing. Once in place, the jacks may be so left, they being of such size that they will be inconspicuous, depending but slightly below the axle housing or axle as the case may be. The relative 110

proportion of axle housing and jack is indicated in Fig. 1. When it is desired to use the jack, a suitable tool may be engaged with the polygonal end 15 of the shaft 14, to rotate the shaft in a direction to extend the lazy tongs. The foot 3 is moved downward and will engage the ground smoothly, regardless of the inclination of the ground, the foot being pivoted to the lazy tongs.

10 The jack is very powerful, and practically any desired power may be obtained by properly proportioning the worm and worm wheel, the screw and nuts, and the length of the levers that constitute the lazy tongs.

15 Preferably the levers of the lazy tongs are in two series, the alternate members being double, and arranged one upon each side of the intermediate series, which are single, and a little less than twice the thickness of

20 a member of the first named series.

I claim:

1. A jack of the character described comprising a substantially rectangular casing open at its bottom and carrying at one side 25 clamping means engageable about the axle of a vehicle, an extension formed at one end of the upper portion of the casing, a shaft journaled through the upper portion of the casing and the extension, said shaft being 30 oppositely threaded adjacent its ends and being limited to rotary movement, the underside of the top of the casing being formed

with a guide groove, nut members slideable along said groove and engaged upon the threaded portions of said shaft, a lazy tongs 35 having the ends of its uppermost links connected with said nut members, a foot member connected with the lowermost links of the lazy tongs, and means for turning said shaft comprising a worm wheel secured 40 thereon within said extension, a shaft journaled through said extension at right angles to said threaded shaft and having one end formed for engagement by a handle, and a worm on said second named shaft meshing 45 with the worm wheel.

2. A jack of the character described comprising a substantially rectangular casing open at its bottom and carrying at one side 50 clamping means engageable about the axle of a vehicle, a shaft journaled through the upper portion of the casing, said shaft being oppositely threaded adjacent its ends and being limited to rotary movement, the underside of the top of the casing being formed 55 with a guide groove, nut members slideable along said groove and engaged upon the threaded portions of said shaft, a lazy tongs having the ends of its uppermost links connected with said nut members, a foot member connected with the lowermost links of the lazy tongs, and means for turning said 60 shaft.

HERBERT A. THORNDIKE.
